No. 11,482

November 4, 1879

UNITED STATES PATENT OFFICE.

SAMUEL C. HAWKINS, OF NEWARK, NEW JERSEY.

DESIGN FOR BUCKLES.

Specification forming part of Design No. **11,482**, dated November 4, 1879; application filed September 16, 1879.
[Term of patent 7 years.]

To all whom it may concern:

Be it known that I, SAMUEL C. HAWKINS, of the city of Newark, in the county of Essex and State of New Jersey, have originated a new Design for Harness-Buckles, of which the following is a full, clear, and exact description, reference being had to the accompanying photographic illustration, making part of this specification.

a represents the side bars, *b* the front bar, *c* the tongue, and *d* the heel, of the buckle.

The novelty of the design, as relates to the top view, consists in the plain broad front bar, *b*, the uniform and narrow edge of the side bars, *a*, the straight tongue *c*, and the heel *d*, as shown in Figure 1, and, as seen in a side view, the plain deep side bars, as shown in Fig. 2.

I am aware of Patents Nos. 110,115, 170,831, and 204,342, and do not claim any of the distinguishing features shown and claimed therein.

What I claim is—

The design for a harness-buckle in which the top view presents a plain broad front bar, side bars having a uniform narrow edge, and a plain straight tongue, the side view presenting a plain deep side bar, as shown in the accompanying illustration.

In testimony that I claim the foregoing I hereto set my hand in presence of two witnesses.

SAMUEL C. HAWKINS.

Witnesses:

OLIVER DRAKE,
H. A. PARMELEE.
